United States - Patent Office.

THOMAS W. BRACHER, OF NEW YORK, N. Y.

Letters Patent No. 95,074, dated September 21, 1869.

IMPROVEMENT IN HAT-VENTILATORS.

The Schedule referred to in these Letters Patent and making part of the same.

To all whom it may concern:

Be it known that I, THOMAS W. BRACHER, of the city, county, and State of New York, have invented a new and improved Hat-Ventilator; and I do hereby declare the following to be a full, clear, and exact description thereof, which will enable those skilled in the art to make and use the same, reference being had to the accompanying drawing, forming part of this specification, in which drawing—

Figure 1 represents an inside view of a hat provided with my ventilator.

Figure 2 is a transverse section of the same.

Figure 3 is a detached sectional view of the ventilating-wire, in a larger scale than the previous figures.

Similar letters indicate corresponding parts.

This invention consists in a hat-ventilator, made of a duplex corrugated strip of sheet-metal, composed of two parts, placed edge to edge, and united by braiding, and secured between the body of the hat and the sweat-leather in such a manner, that said duplex corrugated strip can be readily attached by stitches passing through between its two parts, and thereby the stitches are concealed, and brought in such a position that they are not exposed to corrosion or abrasion, and, furthermore, the corrugated duplex strip being made of two parts, as stated, is more pliable than a single strip of the same width and thickness, and it is better able to adapt itself to the formation of the head.

In the drawing—

The letter A designates a hat which is provided with my ventilator. This ventilator consists of a duplex corrugated strip, a, of sheet-metal or spring steel, made of two parts, b c, (see fig. 3,) which are placed together, edge to edge, and united by braiding, as shown. The threads which form the braiding pass round both parts, and through between them, so that

the strip a, after having been corrugated, can be readily fastened between the body of the hat and the sweat-leather by stitches passing through between the two parts, b c, of said strip, and thereby the stitches are concealed, and not exposed to abrasion or corrosion, whereas if a single strip of corrugated sheet-metal or wire is used, the stitches required for fastening the same to the hat must either pass through holes in the strip or they must be carried round said strip, and in both cases they do not make a good appearance, and they are much exposed to corrosion and abrasion, and the ventilator is liable to work loose after a short time.

Another great advantage of using a duplex strip is, that such a strip is more pliable than a single strip of the same width and thickness, and that the same is better qualified to adapt itself to the formation of the head, without producing a painful feeling or pressure on the same.

I do not claim, broadly, as my invention, a hat-ventilator composed of a single corrugated strip of sheet-metal, such being shown and described in the application of S. G. and W. E. Sturges, rejected October 8, 1860. I am aware that corrugated and zigzag strips of metal have been used as hat-ventilators, and I, therefore, lay no claim thereto; but

What I claim as new, and desire to secure by Letters Patent, is—

A hat-ventilator, consisting of the metal pieces a b, arranged vertically, one above the other, and braided together, to form a fabricated connection between them, through which the stitches pass, to connect the same to the hat, substantially as described.

T. W. BRACHER.
